Harold Renn

UNITED STATES PATENT OFFICE.

HARRY CHARMS, OF NEW YORK, N. Y.

VERNIER DIAL.

Application filed December 11, 1924. Serial No. 755,128.

To all whom it may concern:

Be it known that I, HARRY CHARMS, a citizen of Russia, residing at New York, in the county of New York and State of New York, have invented certain new and useful Improvements in Vernier Dials, of which the following is a specification.

This invention relates to improvements in vernier dials and has as its main object to provide a composite dial, one section of which may be used for approximate settings and another in obtaining extremely accurate readings.

The demand for finely adjustable dials, as used in connection with wireless telephone or radio apparatus, can be met only by a dial capable of two distinct movements, be entirely self-contained, compact and of attractive appearance, and be easily operated by a novice.

With the foregoing features in contemplation, the present invention will be hereafter described and illustrated in the accompanying drawing, the same constituting an essential part of this disclosure, and in which:

Figure 1 is an essentially central longitudinal sectional view of a vernier dial made in conformity with the invention and indicating its application.

Figure 2 is a transverse sectional view taken in the planes indicated by the line 2-2 of Figure 1.

Figure 3 is a fragmentary central section of the same taken in a longitudinal plane.

Referring more in detail to the drawing, a panel, designated by the numeral 10 is used as a support for the structure, which, as illustrated carries a shaft 11 engaged in a variable condenser 12 having fixed stator plates 13 and rotor plates 14, all of the ordinary type of construction.

The portion of the shaft 11 extending through the panel 10 passes into a sleeve 15 having a hub 16 on which is seated a disc 17 held stationary by a screw 18 engaging in the panel and provided with a spacer 19 so that the disc is maintained parallel with the panel, and the disc is held frictionally on the shoulder of the sleeve by a clamp nut 20.

The outer part of the sleeve contains a bored recess 21 into which a tapered screw-threaded extension 22 of the sleeve projects, this extension being split, as at 23, into several parts so as to contact and grip the

end of the shaft 11 by reason of a tapered internally screw-threaded plug 24, fitting the bored recess 21 and having an extending stem 25 terminating in a screw-threaded end 26, the same being engaged in disc 27 rotatably mounted on the outer end of the structure and by which rotary motion may be conveyed directly to the shaft 11.

At the same time a pair of arms 28, rigid with the hub 16, convey motion to a ring 29 to which is secured the inner dial 30, which will thus be moved in accordance with the disc 27 and condenser element 12, giving the usual course adjustment.

A vernier dial 31 is seated in a cavity formed in the inner dial 30 at its periphery, the vernier dial having a cylindrical extending body 32 on which is a knurled ring 33 for convenience in operation.

Another enlargement 34, at the end of the cylinder provides a seat for the disc 27, which covers the bore or chamber 35 in the cylinder, and the cylinder is further supported on the periphery of the fixed disc 17.

Secured in the outer end of the chamber 35 is a ring 36 having arms or spokes 37 fixed in a hub 38 provided with a tubular stem 39 rotatable on the stem 25, and having on its inner surface a spur gear 40.

Fixed on the outer side of the disc 17 is an outstanding bracket 41 offset to one side, and on the opposite side of the disc is another, larger bracket 42, offset in like manner and having at its end a right angled member 43.

A spindle 44 is mounted at one end in the disc 17 to have a bearing in the member 43, its extending end having fixed upon it a pinion 45 in mesh with the gear 38, and formed on the spindle 44 is a helix or worm 46, the axis of which is parallel to the shaft 11.

Another spindle 47 is mounted transversely in the structure, its ends being journaled in the brackets 41 and 42. One end of the spindle is formed to present a worm gear 48 meshing with the worm 46, and midway in the length of the spindle is another worm 49 which meshes with a worm gear 50 formed on a sleeve 51 rotatably mounted on the sleeve 15 and clamped frictionally thereon by the nut 52.

From the foregoing it will be understood that rapid rotation of the disc 27 is conveyed directly to the dial 30, the friction sleeve 51

being sufficiently free to remain quiescent, merely acting as a brake or drag on the shaft.

When the ring 33 is rotated, motion will be conveyed by the ring 36, gear 40, pinion 45, spindle 44, and through the worm transmission 46, 48, 49 and 50 to the sleeve 51, which will, if properly adjusted, transmit a relatively slow motion to the shaft 11, the ratio of reduction being in accordance with the worm gearing in the present case approximately two hundred to one.

Having thus described my invention, and set forth the manner of its construction and operation, what I claim as new and desire to secure by Letters Patent, is:—

1. In a vernier dial, the combination with a spindle, means for actuating the spindle, and a primary dial operated by said spindle, of a secondary dial recessed into the primary dial, a hollow cylindrical extension on the secondary dial, a stationary disc on which the cylinder rotates, means for anchoring said disc to a support, brackets extending from said disc into the chamber in said cylinder, worm gear trains mounted in the brackets, said trains being driven by the rotation of the cylinder, a friction sleeve actuated by the worm gear trains, and means for transmitting motion to said spindle from said friction sleeve.

2. In a vernier dial, the combination with a spindle, means for actuating the spindle, and a primary dial operated by said spindle, of a secondary dial recessed into the primary dial, a hollow cylindrical extension on the secondary dial, a stationary disc on which the cylinder rotates, means for

anchoring said disc to a support, brackets extending from said disc into the chamber in said cylinder, a spindle carried in one of said brackets parallel with the first named spindle, a gear centered on the first named spindle driven by said cylinder, a mating gear on the second spindle, a transverse spindle journalled in said brackets, a sleeve frictionally engaged on the first named spindle to convey motion thereto, worm gear trains engaging the second named spindle with the transverse spindle, and a second worm gear train connecting said transverse spindle and said sleeve.

3. In a vernier dial, the combination with a primary dial, of a sectional shaft, the sections of said shaft being frictionally engaged, means for normally rotating said shaft, means on said shaft to rotate the primary dial, a secondary dial having a hollow cylindrical extension through which said shaft passes, a disc having anchoring means and on which the secondary dial is rotatably mounted, a spindle parallel to said shaft, a spindle transverse to the shaft, both of said spindles being mounted on said disc, a gear on the outer section of said shaft, means actuated by said cylinder to rotate the gear, a pinion on the parallel shaft meshing with the gear, a sleeve frictionally carried by the inner section of said shaft, and worm gear trains on said spindles and sleeve whereby a reduction of speed of the shaft is obtained.

In witness whereof I have affixed my signature.

HARRY CHARMS.
